DEVICE FOR BLACKING SIGHTS OF WEAPONS

David M. Shoup, Bremerton, Wash.

Application August 5, 1936, Serial No. 94,471

4 Claims. (Cl. 93—2)

This invention relates to devices for blacking sights of weapons and has for an object to provide a process of manufacture and a composition of matter comprising a camphor stick coated throughout its entirety with paraffin and particularly adapted for use in blacking sights of weapons as an aid to rifle and pistol marksmanship.

With the above and other objects in view the invention consists of certain novel details of construction and combinations of parts hereinafter fully described and claimed, it being understood that various modifications may be resorted to within the scope of the appended claims without departing from the spirit or sacrificing any of the advantages of the invention.

In the accompanying drawing forming part of this specification,

Figure 1 is a longitudinal sectional view of a cylinder and a rod constituting suitable apparatus for carrying out the first step of manufacture of the product, that is, applying a coating of paraffin to the inner wall of the cylinder.

Figure 2 is a view similar to Figure 1 but showing the apparatus in use for forming a solid cylinder of grated and screened camphor inside of the paraffin cylinder.

Figure 3 is a perspective view of the product equipped with a gummed wrapper.

Figure 4 is a detail longitudinal sectional view of the product with parts in elevation.

Figure 5 is a cross sectional view of the product drawn to an enlarged scale.

Referring now to the drawing in which like characters of reference designate similar parts in the various views, 10 designates a metal cylinder and 11 designates a solid metal rod adapted to snugly fit the cylinder.

In carrying out the process the rod is supplied with a coating 12 of paraffin, preferably by rubbing the rod with a cake of commercial paraffin. The rod is then pushed through the cylinder, this operation of coating the rod with paraffin and pushing the same through the cylinder being repeated until a coating of paraffin has adhered to the inner wall of the cylinder.

In carrying out the second step of the process a supply of powdered camphor 13 is inserted in the cylinder, as best shown in Figure 2, and the rod is then used to transmit the pressure neces-

sary to cause the camphor to assume a solid form coated uniformly throughout with the paraffin coating on the inner wall of the cylinder.

The camphor cylinder, with the paraffin coating transferred thereto, is then forced out of the cylinder 10. A gummed wrapper 14 is now applied to the paraffin coating of the camphor cylinder to complete the process.

In practice it has been found that a practical product of this type comprises approximately 99.9 parts of camphor and .1 of paraffin. The paraffin coating serves to provide a smooth surface which promotes accurate application of the gummed wrapper in an air tight manner which is essential due to the volatilizing characteristics of camphor. The camphor is preferably grated and screened through a 15 mesh screen before being compressed into solid form in the cylinder.

The paraffin coated camphor cylinder is highly effective for use in the blackening of the sights of weapons as an aid to rifle and pistol marksmanship.

From the above description it is thought that the construction and operation of the invention will be fully understood without further explanation.

What is claimed is:

1. The step in a method of manufacturing a device for blacking the sights of weapons consisting of pressing a supply of camphor in finely comminuted form into a paraffin cylinder rigidly supported throughout its entire wall to produce a solid camphor body coated with paraffin.

2. A device for blacking the sights of weapons comprising paraffin coated camphor body, and a moisture resisting combustible wrapper on the paraffin coating.

3. A device for blacking the sights of weapons comprising a solid camphor body, a paraffin coating on the body, and a gummed combustible wrapper applied to the entire superficial area of the paraffin coated body.

4. A device for blacking the sights of weapons comprising, a paraffin coated camphor body, the proportions of camphor to paraffin being substantially camphor 99.9 and paraffin .1, and a moisture repellent combustible wrapper on the paraffin coated body.

DAVID M. SHOUP.
